UNITED STATES PATENT OFFICE.

JASPER E. OSTRANDER, OF BERKELEY, CALIFORNIA.

VENTILATING-FAN.

1,050,994.

Specification of Letters Patent. Patented Jan. 21, 1913.

Application filed December 22, 1911. Serial No. 667,321.

To all whom it may concern:

Be it known that I, JASPER E. OSTRANDER, a citizen of the United States, residing at Berkeley, in the county of Alameda and State of California, have invented certain new and useful Improvements in Ventilating-Fans, of which the following is a specification.

My present invention relates to ventilating fans, and more particularly to that class of devices disposed in wall openings to directly ventilate the room adjoining the wall, or to assist in the ventilation of such. The device is particularly adapted to be conveniently used in buildings where, after construction, the usual ventilating system has been found inadequate and it is desired to provide for a circulation of air, in the rooms, by utilizing the air exteriorly of the room or building, such convenient openings as a window, transom window or the like being used in transferring the air in continuous currents from one place to another.

The principal object of my invention is to provide a device of the character described, which, while efficiently serving the purpose as an air circulator, retards the propagation of sound from one side of the wall to the other substantially the same as would a closed wall opening.

A further object of my invention is to render the device adjustable to regulate the volume of air transferred by the device.

In the drawings, forming a part of this specification:—Figure 1 is an interior elevation of a portion of a window frame inclosing a device embodying my invention. Fig. 2 is a cross sectional view on substantially the lines 2—2 of Fig. 1. Fig. 3 is a fragmentary elevation of a portion of a wall portion. Fig. 4 is a side elevation of the ventilating fan and a fragment of the wall portion it is associated with.

In the drawings, where similar characters refer to similar parts throughout the views, 1 designates a wall portion or screen, preferably of sound proof material, which may be conveniently placed within a window casing 2, the sash 3 thereof being raised to accommodate the former and being in abutting relation thereto, to exclude inclement weather.

The air current producing means includes a revoluble fan 3 provided with a plurality of blades 4 extending crosswise the plane of rotation thereof. The fan may be ro-

tated by an electric motor 5, or any other desired motion generating means, the fan being mounted on the shaft 6 of the motor.

Since it is undesirable to expose a device, such as a motor, to the inclemency of the weather, the wall portion 1 has a slot 7 through which the fan 3 may revolve with its plane of rotation crosswise and diagonal with respect to the plane of the wall portion, the motor 5 then being supported on a bracket 8 secured to the wall portion 1 and wholly disposed on the protected or interior side of the wall portion. By this arrangement, I avoid placing the motor with the axis of its drive shaft parallel and within the plane of the wall portion 1, the center of the fan being, however, substantially in the axis of the latter.

In order to retard the propagation of sound from the one side of the wall to the other, I provide a drum-like housing 9, preferably formed of sector-like portions 10 pivoted to swing about the axis of the shaft 6. These sector-like housing members may frictionally engage the walls of the slot 7 to retain a stationary position, and, as shown in the drawing, are oppositely disposed with respect to each other in the slot. The sectors or members 10 are each at least twice the angular distance between the center lines of the blades, that is, the angular magnitude of each of the lateral walls of each member 10 is substantially that of the angular magnitude between the center lines of two alternate fan blades, as clearly shown in Fig. 2. In this figure, one blade is shown looking directly at its peripheral edge, and wholly inclosed by the section 10, one half of each of the next adjacent blades at either side of the blade referred to is also inclosed by the same section 10, therefore, there are two blades or their equivalent closing the opening which is in communication with both sides of the wall 1 formed by the slot 7 to retard propagation of sound therethrough.

The operation of the device is as follows:—Upon rotation of the fan, air is drawn from one side of the wall 1 and expelled at the other side thereof, and, similarly air is transferred in a like manner in a counter direction. As indicated in Fig. 1, fresh air is entering adjacent the upper margin of the peripheral opening of the drum-like housing 9, and foul air finding egress adjacent the lower margin of such

opening. To control the volume of air entering and leaving the room, the members 10 of the housing 9 may be swung on their axes and brought near together, or spaced 5 apart from each other as desired, and further, the air expelled may be directed to flow, as desired, by manually moving the members 10 providing for ingress of air, and similarly, the members 10 providing for 10 egress of air, may be manually moved to draw in the current, as desired, the members retaining their adjusted position by friction contact with the margins of slot 7.

Inasmuch as two or more of the blades 15 of the fan are ever within the housing 9, at that portion thereof intermediate the transverse margins of the openings therein, when the parts are in assembled operative relation to each other, the sounds are not 20 readily propagated through such obstructions and consequently the intensity of the sound on one side of a wall, is substantially no greater than would be if openings were entirely closed, as with a glazed sash or 25 the like.

I claim:—

1. The combination with a wall portion having a slot, of a rotatable fan, disposed with its plane of rotation passing through 30 the slot in the wall portion, and a drum-like housing for said fan disposed in said slot in said wall portion and having peripheral openings at both sides of the latter, said housing being adapted to house two or more 35 of the blades of the fan, at that portion of the housing intermediate the transverse margins of the opposite openings thereof, substantially as and for the purpose set forth.

40 2. The combination with a wall portion including a slot, of a rotatable fan, disposed with its plane of rotation passing through the slot in the wall portion and diagonally with respect to the plane of the latter, a 45 drum-like housing for said fan disposed in said slot in said wall portion and having peripheral openings at both sides of the lat-

ter, said housing being adapted to house two or more of the blades of the fan, at that portion of the housing intermediate the 50 transverse margins of the opposite peripheral opening thereof, substantially as and for the purpose set forth, and means disposed adjacent one side of the wall portion for rotating said fan. 55

3. The combination with a wall portion having a slot, of a rotatable fan, including a plurality of radially extending blades disposed crosswise the plane of rotation thereof, said fan being disposed with its 60 plane of rotation passing through the slot in the wall portion, and a housing for said fan, including oppositely disposed sector-like portions disposed in the said slot in said wall portion, the angular magnitude 65 of the walls of said sector-like portions being substantially equal to the angular disposition of the radial axes of two alternate fan blades, substantially as and for the purpose set forth. 70

4. The combination with a wall portion, having a slot, of a rotatable fan, including a plurality of radially extending blades disposed crosswise the plane of rotation thereof, said fan being disposed with its plane 75 of rotation passing through the slot in the wall portion, and a housing for said fan including sector-like portions oppositely disposed with respect to each other in engaging relation to the walls of the said slot in said 80 wall portion and pivotally mounted to swing about the axis of rotation of said fan, the angular magnitude of the walls of said sector-like portions being substantially equal to the angular disposition of the radial axes 85 of two alternate fan blades, substantially as and for the purpose set forth.

In testimony whereof I affix my signature in presence of two witnesses.

JASPER E. OSTRANDER.
